CLAIM

The ornamental design for an outsole for footwear, as shown and described.

DESCRIPTION

FIG. 1 is a first perspective view of my ornamental design for an outsole for footwear;

FIG. 2 is a front view thereof;

FIG. 3 is a rear view thereof;

FIG. 4 is a bottom view thereof;

FIG. 5 is a right side view thereof;

FIG. 6 is a left side view thereof; and,

FIG. 7 is a second perspective view thereof.

The broken lines show environmental structure that forms no part of the claimed design.
